L. A. THOMAS,
COMBINATION DISCONNECTING SWITCH, FUSE, CHOKE COIL, AND LIGHTNING ARRESTER.
APPLICATION FILED OCT. 8, 1917.

1,287,138.

Patented Dec. 10, 1918.

UNITED STATES PATENT OFFICE.

LUCIAN ALVAH THOMAS, OF NEW YORK, N. Y.

COMBINATION DISCONNECTING-SWITCH, FUSE, CHOKE-COIL, AND LIGHTNING-ARRESTER.

1,287,138.

Specification of Letters Patent. Patented Dec. 10, 1918.

Application filed October 8, 1917. Serial No. 195,287.

To all whom it may concern:

Be it known that I, LUCIAN ALVAH THOMAS, a citizen of the United States, residing at New York city, in the State of New York, have invented certain new and useful Improvements in Combination Disconnecting-Switches, Fuses, Choke-Coils, and Lightning-Arresters; and I do hereby declare the following to be a full, clear, and 10 exact description of the invention, such as will enable others skilled in the art to which it appertains to make and use the same.

My invention relates to a combination disconnecting switch, fuse, choke coil and 15 lightning arrester.

One object of my invention is to provide a simple, cheap and efficient combination of a disconnecting switch, fuse, choke coil and lightning arrester so constructed that it 20 shall be self-contained and capable of being readily mounted upon cross arms, walls of buildings or any other suitable supporting structure.

A further object of my invention is to 25 provide such a combination so constructed that some of the elements may be omitted without impairing the efficiency of the remaining elements.

A further object of my invention is to 30 provide such a combination so constructed that a plurality of the combinations may be mounted in juxtaposition and operated simultaneously, if desired.

A further object of my invention is to so 35 construct the combination that a minimum of insulators will be required.

A further object of my invention is to construct such a combination which shall 40 be extremely compact and occupy but small space upon the cross arms to which it is attached and thus permit of a minimum length of pole being used.

These and further objects of my invention will become apparent from the description 45 and explanation of the construction and operation of my improved combination disconnecting switch, fuse, choke coil and lightning arrester in the following specification, reference being had to the accompanying 50 drawings, in which:

Figure 1 is a side view of my improved combination disconnecting switch, fuse,

choke coil and lightning arrester shown attached to a pair of cross arms, the latter being supported by a pole.

55

Fig. 2 is a view of the parts shown in Fig. 1 looking in the direction of the arrow 2.

Fig. 3 is a central section of the movable switch member and coöperating parts taken along the line 3—3 in Fig. 1 looking in the 60 direction of the arrow 2.

Figs. 4 and 5 are details of parts herein-after referred to.

65

Fig. 6 is a detail view of the switch locking mechanism.

Fig. 7 is a view of the parts shown in Fig. 5 looking in the direction of the arrow 6.

In the drawings:

10 represents a pole or a member of any suitable support to which are attached the 70 cross arms 11—11 by means of the lag bolts 12—12. The base 13 is formed of the knee piece 14, the flat plate 15 and the side pieces 16—16. The side pieces 16—16 are riveted to the knee piece 14 and the plate 15 by 75 means of rivets such as 17. The base 13 is secured to the cross arms 11—11 by means of lag bolts such as 18. Insulator supports 19 and 20, preferably formed of metal, are riveted or otherwise secured, respectively, to the outer ends of the supports 19 and 20. A switch fork 23 is supported by the insulator 21 and a pair of switch blades 24 is 80 supported by the insulator 22, the functions of the insulators 21 and 22 being to insulate, respectively, said fork and pair of blades from the supports 19 and 20.

The switch member 25 is formed of the 90 insulating tube 26, the latter being provided at its lower end with the metallic fulcrum plug 27. The fulcrum plug is provided at its lower end with a flat portion 28 having the hole 29. The flat portion 28 fits snugly between the prongs 30—30 of the fork 23 and the pin 31 passing through holes provided in said prongs and the hole 29 in the flat portion 28 serves to articulate the fulcrum plug 27 with the fork 23.

95

The tube 26 is provided at its upper end with the metallic knife plug 32, the latter having at its upper end the knife portion 33, the inner edge of the knife portion 33

100

being beveled as at 34, so that the knife portion 33 may readily enter between the switch jaws 24.

As shown in Fig. 3, the plugs 27 and 32 are formed with cylindrical portions 35 and 36, respectively, adapted to fit snugly within the interior of the insulating tube 26, and said portions are secured within said tube in any approved manner. Cylindrical portions of approximately the same diameter as the outer diameter of the insulating tube are provided, respectively, between the cylindrical portions 35 and 36 and the flat portion 28 and knife portion 33.

15. In order to secure the switch member 25 in the position shown in Figs. 1 and 2, the following instrumentalities are provided:—

The switch lock 37 is composed of the two ears 38—38 (see Figs. 3 and 7), adapted 20 to loosely embrace the upper end of the knife portion 33, said portion and ears being provided with holes through which loosely passes the pin 39 which articulates the switch lock 37 to the knife portion 33. 25 The ears 38 are provided with holes 40—40 for the reception of the operating hook, as hereinafter described. The pin 39 is provided as at 41 with a stud shaped portion having the enlarged head 42 between which 30 and the side of one ear 38 there is mounted the coil spring 43 having the spring arm 44, the latter resting between the pins 45—45 which are secured in the switch lock 37.

The bottom of the slot between the ears 35 38—38 is cut so that it bears against the edge 46 of the knife portion 33 and thus forms a stop for the switch lock 37, the pressure of the spring arm 44 holding said bottom against said edge, as shown in Figs. 40 1 and 6. The upper edge of the knife portion 33 is beveled as at 47 (see Fig. 6) so that the switch lock 37 may be moved by the operating hook into the position shown dotted in Fig. 6 when the switch member 25 45 is to be moved backward into the position shown dotted in Fig. 1.

A switch latch 48 (see Fig. 6) is provided between the switch jaws 24—24, the upper edge of said latch being beveled as at 49 for 50 a purpose hereinafter explained. The latch 48 is of such thickness that when the edge of the knife portion 33 is resting against same the outer face of the nose 50 of the switch lock 37 will be resting against the 55 inner surface thereof. The end of the nose 50 is beveled as at 51 for a purpose herein-after explained.

On the knife plug 32 there is mounted the 60 petticoat insulator 52 which serves to shield the joint between said plug and the insulating tube 26 from the action of the weather, and just below the insulator 52 there is 65 mounted the horn clamp 53. The connector clamp 54 is clamped around the fulcrum plug 27. Said clamp consists of the clamp-

ing portions 55 and 56 which are secured together by the bolts 57—57. The portion 55 is formed integrally with the arm 58, the latter terminating in the boss 59, having a central hole in which is mounted one end of 70 the connector 60, the latter being secured in place in said boss by means of the screw 61.

In order to shield the joint between the fulcrum plug 27 and the tube 26 and the connection between the clamp 54 and the 75 fulcrum plug 27, the petticoat insulator 62 is mounted upon the tube 26 with its lower edge just above the upper edge of the clamp 54.

Just above the upper edge of the insulator 80 62, a second horn gap clamp 63, similar to the horn gap clamp 53, is secured to the tube 26. The horn gap clamp 53 consists of the portions 64 and 65 which are secured together by means of the bolts 66—66. The 85 portion 64 is provided with the arm 67, the upper end of which is provided with a threaded hole in which is screwed the screw 68 and having the washer 69 mounted thereupon, between which and the arm 67 there is 90 secured one end of the discharge horn 70.

The horn 70 is preferably formed of wire shaped as shown in Fig. 1 and having one end secured to the arm 67, as just described, and the other end secured by means of the 95 screw 71 between the washer 72 and the arm 73 of the horn gap clamp 63.

The fuse 74 is placed within the insulating tube 26 and the upper end of said fuse is connected in any approved manner to the 100 knife plug 32; the lower end of the fuse 74 passes through the hole 75 provided in the tube 26 and is secured to the clamp 63 by means of the screw 76.

A petticoat insulator 77 is secured to the 105 tube 26 just above the clamp 63 and serves to shield the connection between the fuse 74 and the latter and the hole 75 from the weather.

Just above the insulator 77 a second connector clamp 78, similar to the connector clamp 54, is secured to the tube 26 and the upper end of the connector 60 is secured in 110 the boss of the clamp 78 by means of the screw 79.

The choke coil 80 is wound around the insulating tube 26 between the clamps 53 and 78, the upper end of said coil being secured to the former clamp by means of the bolt 81 and to the latter clamp by means of the 120 bolt 82.

A metallic post 83 is riveted or otherwise secured in the horizontal member of the knee piece 14, said post supports the petticoat insulator 84 and the latter supports at 125 its top the triangular discharge horn 85, which is preferably formed of a metallic wire. A second discharge horn 86 is secured to the horizontal member of the knee piece 14 in any approved manner, as by 130

means of the bolt 87, and a resistance 88, formed of any suitable material and having any suitable ohmic resistance, has its upper end connected in any approved manner to the discharge horn 85 and its lower end connected to the knee piece 14, the latter being connected as by means of the ground wire 89 to the ground. The line wire 90 connects from the line to the switch blades 24 and the line wire 91 connects from the switch fork 23 to the electrical apparatus that is to be protected.

It is evident that all the line wires required for any piece of apparatus will be connected similarly to 90 and 91, there being one of my improved combinations of disconnecting switch, fuse, choke coil and lightning arrester used for each line.

The operation of my improved combination disconnecting switch, fuse, choke coil and lightning arrester is as follows:

The switch member 25 is supposed to be in the position shown in Figs. 1 and 2 with the switch lock 37 securing it in place by reason of the fact that the nose 50 thereof is behind the switch latch 48.

The line current then enters through the wire 90 to the switch blades 24, it then passes to the knife portion 33, thence to the knife plug 32, thence to the fuse 74, thence to the clamp 63, thence through the discharge horn 70 to the clamp 53, thence through the choke coil 80 to the clamp 78, thence through the connector 60 to the clamp 54, thence through the fulcrum plug 27 to the prongs 30 and thence through the wire 91 to the apparatus that is to be protected.

The path just described is the path followed by the line current under ordinary conditions, but should a lightning discharge enter by the wire 90 it will follow the same path until it reaches the discharge horn 70.

At this point there is a choice of paths for the high potential, high frequency lightning discharge,—one across the gap between the horns 70 and 85 and the other through the choke coil 80 and the rest of the path above described to the wire 91 and thence to the apparatus to which 91 is connected.

But owing to the high impedance of the choke coil 80 to the high frequency lightning discharge the latter jumps the gap between the horns 70 and 85 and from the horn 85 the lightning discharge has a choice of two paths,—one across the gap between the horns 85 and 86 to the ground wire 89 and the other through the non-inductive resistance 88 to the ground wire 89.

The lightning will jump the gap between the horns 70 and 85 and in all probability will jump the gap between the horns 85 and 86 and the line current being of much lower potential and frequency will be unable to jump the two gaps and even if it jump the

first gap, it will pass to the ground wire 89 through the resistance 88.

The resistance 88 is made of such a value that it will so limit the line current that might pass the gap between the horns 70 and 85 that the line voltage would be unable to maintain an arc across said gap.

When it is desired to use my improved combination disconnecting switch, fuse, choke coil and lightning arrester, the operator uses a pole provided with any approved form of hook, the latter of which he introduces within the holes 40 of the switch lock 37 and pulling downward upon the pole, he moves said lock to the position shown dotted in Fig. 6, thus removing the nose 50 from engagement with the latch 48 and then a further downward pull upon the pole will move the switch member 25 to the position shown dotted in Fig. 1 or at any other angular position in a clock-wise direction therefrom that may be desired.

When the switch member 25 is to be restored to close the circuit, the hook is placed within the holes 40 as before described, and the pole moved upward. This will introduce the knife portion 33 within the jaws 24 and the beveled edge 51 of the switch lock 37 will strike the beveled edge 49 of the switch latch 48 and cause the latter to relieve slightly, thus permitting the nose 50 to pass over the latch 48 into the position shown in Fig. 6.

It is evident that certain of the features of my improved combination may be omitted and the others used alone. For instance, the switch member 25 may be used alone as a switch without the use of the discharge horn 70, the fuse 74, the choke coil 80, the discharge horns 85 and 86 and the non-inductive resistance 88. When these parts are omitted the switch member will act simply as a disconnecting switch.

Or the switch member 25 may be fixed permanently in position and the rest of the combination used as a lightning arrester combined with the choke coil and fuse.

Or from the combination noted in the last paragraph, the choke coil and fuse may be omitted.

Thus it will be evident that my improved combination may be used as illustrated in the drawings or separate features thereof may be used alone, if desired, or in other combinations.

I claim:

1. The combination with a switch member comprising an insulating tube and a knife plug secured in one end thereof, of a clamp upon the exterior of said tube, a fuse located within said tube and having one end connected to said plug and the other end connected to said clamp, a second clamp upon said tube and a discharge horn secured to said clamp.

2. The combination with a switch member comprising an insulating tube and a fulcrum plug and a knife plug secured in the ends thereof, of a choke coil and discharge horn 5 mounted upon the exterior of said tube, one end of each of said coil and horn being connected together and the other ends thereof respectively being connected to said fulcrum and knife plugs.
- 10 3. The combination with a switch member comprising an insulating tube and a fulcrum plug and a knife plug secured in the ends thereof, of insulators mounted upon said member and located to shield the joint between said tube and plugs.
- 15 4. The combination with a switch member comprising an insulating tube and a fulcrum plug and a knife plug secured in the ends thereof, a connector clamp secured to 20 said fulcrum plug, a second connector clamp

secured to said tube, a connector secured in said clamps, a pair of horn clamps secured to said tube, a discharge horn secured to said clamps, a connection between said second connector clamp and one of said horn clamps 25 and a fuse connected between the other horn clamp and said knife plug.

5. The combination with a base, of a pair of insulators supported thereby, a pair of prongs supported by one of said insulators, 30 a switch member fulcrumed to said prongs, a pair of jaws supported by the other of said insulators and adapted to receive said member, a horn supported by said member, a third insulator supported by said base, a 35 second horn supported by said third insulator and located in juxtaposition to said first-named horn.

In testimony whereof, I affix my signature.
LUCIAN ALVAH THOMAS.
